United States Patent Office.

PHILLIP ESSER AND FRANKLIN A. STEERE, OF NORTH PROVIDENCE,
RHODE ISLAND.

Letters Patent No. 78,077, dated May 19, 1868.

IMPROVED MACHINE FOR SETTING BUTTON-HOOKS.

The Schedule referred to in these Letters Patent and making part of the same.

TO ALL WHOM IT MAY CONCERN:

Be it known that we, PHILLIP ESSER and FRANKLIN A. STEERE, both of North Providence, in the county of Providence, and State of Rhode Island, have invented a new and improved Machine for Setting Button-Hooks; and we do hereby declare that the following specification, taken in connection with the drawings, making a part of the same, is a full, clear, and exact description thereof.

Figure 1 exhibits the machine in perspective.

Figures 2, 3, and 4 are detailed parts to be referred to.

Our machine is designed to afford a means for conveniently inserting in shoes and gaiters that article known as a "combined hook and button," which is described and shown in the Letters Patent granted to William H. Shurtleff, of Providence, Rhode Island, dated June 5, 1866, and which, for holding lacings for shoes and like purposes, is intended to supersede the use of eyelets.

The drawing represents a hand-tool, but the same principles which are employed in it can be equally well embodied in a machine to be operated by power.

The article referred to as a combined hook and button consists of a metallic button-head set upon a crooked neck, and furnished with three prongs, which prongs are intended to be inserted in the material to which the article is to be affixed, and clinched upon the back side thereof, leaving upon the face side of the material in sight only the crooked neck surmounted by a button-head.

In the particular instance shown in the drawings, A A' are jaws held together by a pivot-pin, a, and being intended for a hand-machine, are furnished with handles like a pair of well-known pliers. The upper jaw may be furnished with an adjustable stop, b, or other convenient device for limiting the distance within which the jaws can be opened. The lower jaw is furnished with a sided block, B, having three rectangular faces of equal size, and two sides in the form of equilateral triangles. The end of the lower jaw A' is made forked, and the block is mounted in the opening formed by the forks, so that it can be revolved upon a pin, c, passing through the sides of the fork and the triangular faces of the block.

A spring-pawl, d, fig. 4, is attached to the upper jaw, and is so arranged with reference to the block B that upon opening the jaws A A' to their full extent the block will be made to turn one-third of a complete revolution upon its axis, while during the movement of the jaws in closing, the flat face of the spring-shank of the pawl will bear against one of the sides of the block, and hold it in that position until the next movement of the jaws in opening.

The several faces of the block are as shown in figs. 2, 3, and 4. The first is provided with three holes corresponding in position and in depth with the arrangement and length of the three prongs of the button-hook, as shown in fig. 1. The second face is furnished with a depression in the form of a segment of a hollow sphere. The third face presents a smooth surface.

The operation of the apparatus is as follows: The button-hook is hung by its neck in the receptacle E, especially made for the purpose, upon the upper jaw, that face of the block B being uppermost which is furnished with holes corresponding in number and arrangement to the prongs of the button-hook.

The piece of leather or other material to which the button-hooks are to be attached is now held in position and the jaws are made to close. This causes the sharp prongs of the button-hook to pierce the material, and being forced through it protrudes beyond the under side, the button-hook being all the time retained in the receptacle E.

The next movement of opening the jaws causes the protruding ends of the prongs to be withdrawn from the holes in the block, and the block itself to be rotated, so as to cause the face shown in fig. 2 to be uppermost. The next movement of the jaws in closing bends the ends of the prongs inward toward a common centre. The jaws being again opened, the block is again rotated, so that its smooth face is uppermost, when, the jaws being

again made to approach each other, the ends of the prongs are pressed down flat against the under surface of the material, and the button-hook is securely set.

Upon opening the jaws for the last time, prior to disengaging from the apparatus the button-hook which has just been set, the block is again rotated, so as to present uppermost the face shown in fig. 1, and ready for a repetition of the first operation to be performed in setting the next button-hook in the jaws.

What we claim as our invention, and desire to secure by Letters Patent, is—

1. A machine for setting button-holes, consisting of a revolving block, B, with acting faces, as described, in combination with the spring-pawl *d* and jaws A A, operating substantially as set forth.

2. Constructing the jaw A with a receptacle, E, for the button-hook, so as to hold and sustain the same while it is being inserted and its prongs clinched, substantially as shown and is worked.

PHILLIP ESSER,
FRANKLIN A. STEERE.
